UNITED STATES PATENT OFFICE.

NORRIS J. SAULS, OF PLANT CITY, FLORIDA.

SAFETY DEVICE FOR RAILROADS.

1,348,056.

Specification of Letters Patent.

Patented July 27, 1920.

Application filed November 13, 1918. Serial No. 262,316.

To all whom it may concern:

Be it known that I, NORRIS J. SAULS, a citizen of the United States, residing at Plant City, in the county of Hillsborough 5 and State of Florida, have invented new and useful Improvements in Safety Devices for Railroads, of which the following is a specification.

This invention relates to a safety device 10 for railroads.

In carrying out the invention it is my purpose to produce means for automatically stopping a train approaching a burnt or otherwise destroyed bridge or trestle.

15 It is my purpose to arrange upon a railway trestle weighted elements normally held against movement by fusible or readily breakable means, which means, however, is of sufficient strength to withstand the vibration 20 to which the trestle is subjected incident to the rolling stock passing thereover, the said weighted means controlling suitable trips arranged to the opposite sides of the trestle and held normally in inactive 25 position, but brought to active position to engage with a valve connected with the air system of a train approaching the trestle, to open such valve and to actuate the brakes of the train, when the weighted elements 30 have dropped by the destruction of the fusible connecting means or by the breakage thereof, incident to the destruction of the bridge by burning or from other causes.

The drawings, accompanying this specification 35 illustrate a simple and satisfactory embodiment of the present invention, and in the said drawings:

Figure 1 is a top plan view illustrating the improvement;

40 Fig. 2 is a side elevation thereof;

Fig. 3 is a similar view but showing the arrangement of parts when the weighted elements have dropped and also illustrating the contact members in position to actuate 45 the bleed valve on the air brake system of a train;

Fig. 4 is a sectional view approximately on the line 4—4 of Fig. 1;

Fig. 5 is a perspective view of the bleed 50 valve and the operating levers therefor;

Fig. 6 is an approximately central longitudinal sectional view through the same; and

Fig. 7 is a sectional view approximately 55 on the line 7—7 of Fig. 5.

In the drawings a railway track 10 passes

over a culvert, stream or the like and has its ties 11, at this portion of the track supported upon a trestle 12.

The trestle 12 at its center, and adjacent 60 the ends thereof is provided with transverse rods 13 respectively. These rods not only project beyond the sides of the rails but preferably extend beyond the sides of the trestle and provide shafts for parallel spaced 65 arms 14 which have connected to the outer ends thereof weighted, preferably cross sectionally square, members 15. The weights are so hung that the same will be received between the ties 11 and the trestle, and the 70 same are held in such position by fusible plates 16 secured in any desired or preferred manner to the under faces of the ties. It is here to be stated that the fusible plates may be of easily breakable material, but are 75 sufficiently strong to withstand the vibration to which the trestle is subjected, under all conditions.

Centrally journaled on one of the end and on the center rods 13, at the opposite 80 sides of the trestle 12 are levers 17. These levers have their lower ends hook-shaped as at 18, the said hooks engaging with the arms 14 of the respective weighted elements 15, and being held in one position by such 85 engagement. Oppositely disposed pairs of levers have their upper ends connected by links 19, and the outer levers have their upper ends connected with rods 20 which, of course, extend in opposite directions with 90 respect to the track 10. Preferably, but not necessarily, the rods 20 each comprise two members having their confronting ends threaded and engaged by turn buckles whereby proper adjustments may be made 95 to the said rods.

Certain of the ties upon which the rails of the main tracks rest, at a suitable distance to the opposite sides of the trestle 12 are widened, or suitable supporting blocks may 100 be arranged at these points, and upon these blocks are pivotally connected substantially U-shaped trips 21, each of the said trips having its inner arm provided with an extension 22 to which the outer end of the 105 respective rods 20 are connected. The trips 21 normally rest flat upon their supports, and are held in such position by the engagement of the levers with the arms of the weighted elements 15, but it will be apparent that should the fusible plates 16 melt, incident to the trestle catching on fire or 110

should the said plates break incident to the breaking or bending of the trestle the weighted elements will swing to a vertical position, and actuating the lever 17 and rods 5 20 will swing the trip members 21 to their vertical position. The outer arm of each of the trips 21 is provided with an offset portion 23 which, contacting with the support holds the said trip in its vertical position.

10 On the locomotive 24 which travels in either direction over the track 10 is arranged a bleed valve 25 that is connected with the air brake system for the locomotive and for the train hauled by the locomotive. In the 15 present instance, the valve 25 is normally closed, being influenced by a spring 26 arranged upon a yoke 27 that straddles the pipe 28 to which the valve is connected. On the pipe 28 is secured a collar 29, preferably 20 in the nature of a split member having its ends extended in spaced parallel relation, and passing through these ends is the inner end of an L-shaped trip member 30. The angle portion of the trip member 30, which 25 passes through the ends of the collar, and which is indicated for distinction by the numeral 31 also engages in an eye 32 provided upon a crank lever 33, one end of the lever being loosely connected as at 34 to the 30 yoke 27 and the other end being provided with a flat extension 35 that is contacted by a spring 36 mounted upon a suitable pin 37 arranged upon a casing 38 surrounding or connected with the pipe 28. The trip 30 is 35 always in a position to engage with the contact member or trip 31 of a track construction when the latter is swung to its vertical position, and engagement between these trips will open the pipe 28 to the atmosphere, 40 causing the application of the brakes, in the well known manner, and thus halting the train before the same reaches the trestle.

From the foregoing, the simplicity and advantages of the construction will, it is 45 thought, be apparent, but it is to be understood that the nature of the invention is such

that the same is susceptible to changes in minor details thereof, and that I reserve the right to make all such departures from the drawings and specification as fall within the 50 scope of what is claimed.

Having thus described the invention, what is claimed as new, is:—

1. A means for braking an engine approaching a trestle in the event of the trestle being damaged by fire or other causes, comprising a divided trip at one side of a track which crosses the trestle, a rod connected to said trip, levers arranged in opposed pairs pivoted to the sides of the trestle, weighted means connected on the opposed pairs of levers, fusible and brakable plates connected to the under face of the trestle and supporting thereon the weighted means of the confronting pairs of levers and causing the said pairs of levers to assume opposite angular positions, and connecting means between the rod and levers for normally retaining the trip in its lower horizontal position. 55

2. A means for braking an engine approaching a trestle in the event of the trestle being damaged from fire or other causes, comprising a substantially U-shaped trip having its parallel arms offset and pivoted to one side of a track which crosses the 75 trestle, one of the offset ends having an extension providing a stop for holding the trip in vertical position, a pivoted rod connected to the opposite offset end of the trip, levers arranged in opposed pairs journaled 80 at the opposite sides of the trestle, weighted means connected to each opposed pair of levers, fusible and brakable plates connected to the under face of the trestle, and supporting thereon the weighted means of the confronting pairs of levers for holding such pairs of levers at opposite angles, and adjustable connecting means between the rod and levers normally sustaining the trip in its lower horizontal position. 85

In testimony whereof I affix my signature.
NORRIS J. SAULS. 90
